US00D882117S

(12) United States Design Patent (10) Patent No.: US D882,117 S
(45) Date of Patent: * Apr. 21, 2020

(54) TRAFFIC BARRIER

(71) Applicant: Brad Bonessi, Miami Beach, FL (US)

(72) Inventor: Brad Bonessi, Miami Beach, FL (US)

() Term: 15 Years

(21) Appl. No.: 29/635,663

(22) Filed: Feb. 1, 2018

(51) LOC (12) Cl. 25-02

(52) U.S. Cl. USPC D25/38.1

(58) Field of Classification Search

USPC D10/110, 113.1, 113.2, 113.3; D25/38.1,
D25/40, 100, 101, 199
CPC A01G 9/025; E01F 15/02; E01F 15/065;
E01F 15/08; E01F 15/081; E01F 15/086

See application file for complete search history.
